UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

LIP-TURNING MACHINE.

Application filed May 2, 1925. Serial No. 27,513.

This invention relates to lip turning machines. As herein shown the invention is embodied in a machine which is particularly adapted for operating upon outsoles for McKay sewed shoes, although in some aspects the invention is not necessarily limited to such use but may advantageously be employed to operate upon soles of other types.

The outsole for a McKay sewed shoe is 10 channeled along the margin of its tread face and the lip or flap formed by the channeling operation must be raised to open the channel for the reception of stitches or other fastening means by which the sole is to be secured to 15 the shoe. In order to insure that the groove which is usually provided at the base of the channel lip shall be effectively exposed for the reception of the stitches and further to insure that the channel flap, after being 20 raised, shall not interfere with the effective operation of the stitching devices, it is usually considered desirable to have the lip turned over against the face of the sole and flattened out or set sufficiently to insure that it will not 25 become displaced during such stacking and handling of the sole as may occur after the channel has been opened and before the stitching operation takes place.

One object of the present invention is to 30 provide improved lip turning means for operating upon a lip after it has been preliminarily raised somewhat above the plane of a sole, to turn the raised lip over toward the face of the sole more effectively and with 35 greater uniformity of results upon soles of different styles than in machines heretofore employed for this purpose and also to turn the lip in a manner to insure against possible injury to the lip while it is being turned.

With this object in view, one feature of the 40 invention consists in the combination, with means for continuously feeding a lipped sole, of means for exerting a wiping action upon the moving lip at right angles to the length 45 of the lip to turn the lip over toward the face of the sole. The wiping means herein shown and described comprises a plurality of yielding wiping members which are distributed around the periphery of a driven wheel and 50 which are mounted in such a manner that while the wheel is rotating each wiping member will normally be maintained in an outer position by the action of centrifugal force.

The wheel is further so arranged, relatively to the preliminarily raised lip of a sole which 55 is presented thereto, that rotation of the wheel will cause the wiping members yieldingly to engage the lip in succession, each member delivering a hammer-like blow substantially at the base of the lip and thereafter 60 wiping yieldingly across the lip substantially in a direction at right angles to the edge of the work and to the direction of work feed. This combined beating and wiping action results in effectively breaking down the resistance 65 of the lip and causes it to be turned easily and effectively set in the desired position in a manner in simulation of well-known hand methods of turning a lip which involve pounding the lip by means of a shoemaker's 70 hammer. To insure that the direction of the wiping movement shall be maintained at right angles to the length of the lip while the sole is being advanced continuously at a substantial rate of speed, and also to avoid possible 75 injury to the lip and interference with the feed of the work such as would tend to slow up its advance through the machine, the lip turning means is so organized and operated that not only are the wiping members 80 caused to move transversely across the lip but they are also rendered capable of moving bodily in the direction of work feed as they travel across the lip. Thus, the wiping members are enabled to partake of the advancing 85 movement of the lip while they are in engagement therewith and as a result the feed of the sole is not retarded to any appreciable extent by the wiping action although the wiping members engage the lip in rapid succession.

In the illustrated embodiment of the invention the movement of the wiping members in the direction of feed is provided for by mounting them with provision for end play 95 between disk-like members constituting the opposite sides of the wiping wheel and each wiping member is acted upon by a light spring finger which urges the member in a direction opposite to the direction of feed and which functions, after the member has been displaced by engagement with the lip, to return the member into normal position in the plane of rotation of the other wiping members. Not only are the wiping members adapted to yield 100 as above described but they are made in the 105

form of rollers and are so mounted that they are capable of turning so that they will roll over the lip instead of wiping across it in case the lip offers unusual resistance to turning.

5 The wiping members are also capable of tilting or angularly adjusting themselves lengthwise of the lip to accommodate irregularities of lengthwise contour of the lip. The yielding character of the hammer-like blows and 10 subsequent wiping actions of the wiping members enable them to adapt themselves readily for operation upon soles which differ in thickness and insure against tearing or otherwise injuring the material operated upon.

15 Another object of the invention is to provide improved means to insure that the work shall be adequately supported and positively fed while the lip turning means is operating thereon.

20 To this end and in accordance with a further feature of the invention, the feeding means comprises feed wheels rotatable about parallel axes and arranged to feed a sole by engagement with opposite sides of the sole margin in the plane of rotation of the lip turning device. As herein shown, the feeding means comprises a feed roll arranged with its axis at an angle to the axis of the lip turning device, the periphery of the feed roll being 25 beveled or transversely inclined with respect to its axis, and a second feed roll also having a beveled periphery for engaging the opposite side of the sole margin and co-operating with the first feed roll firmly to grip the sole and to feed it past the lip turning device. The feed roll which engages the margin at the lipped side of the sole is cupped or recessed to receive a portion of the periphery of the lip turning device, thus enabling said feed 30 roll to be located closer to the axis of the lip turning device to insure feeding engagement with the sole margin at the base of the lip or, in other words, in a region closely adjacent to the point of operative engagement of said device with the work. The feed rolls are adapted to engage a substantial width of the sole margin to insure that the work will be firmly held and positively fed. The angles of bevel of the peripheries of the feed rolls are such 35 that the sole margin is gripped less tightly along its outer than along its inner portions thereof, thus enabling the sole to be swung readily to maintain operative engagement of the lip turning device with the lip along the curved portions of the sole margin without undue frictional rubbing or twisting of the sole over the feed rolls, and further insuring against any tendency of the sole to ride out from the grip of the rolls as it is being fed.

40 Furthermore, the angle of bevel of the lower feed roll is such as to insure against any tendency of the edges of the roll to dig into the face of the sole as the abruptly bent portion at the junction of the shank and forepart passes between the feed rolls. Thus, not only is injury

to the stock prevented but the lower feed roll is enabled to maintain engagement with the sole throughout the entire width of the roll during the period of operation in the vicinity of the break between the shank and forepart 70 of the sole, thus preventing the advance of the sole from being temporarily arrested at this point. Further, as herein illustrated, the lower feed roll is made of very small diameter to avoid any possibility of breaking down or 75 flattening out the more or less sharp angle between the shank and forepart of the sole.

The invention further consists in the features of construction and combinations and arrangements of parts hereinafter described 80 and claimed the advantages of which will be obvious to those skilled in the art.

Referring now to the accompanying drawings,

Fig. 1 is a view partially in side elevation and partially in section of a machine constructed in accordance with the present invention;

Fig. 2 is a front elevational view of the machine, a portion of the casing being shown in section;

Fig. 3 is a perspective view showing particularly the construction of the lip turning wheel and illustrating its mode of operation upon the work;

Fig. 4 is a view partially in section and partially in elevation showing particularly the lip turning wheel and the feed wheels;

Fig. 5 is a detail elevational view of a leaf spring member associated with the lip turning wheel;

Fig. 6 is a sectional detail view illustrating the manner in which the sole margin is gripped by the feed wheels;

Fig. 7 is a sectional view showing an alternative form of lip turning wheel, and

Fig. 8 is an edge view of the lip turning wheel shown in Fig. 7, this view showing also the manner in which the wheel is mounted and the relation thereto of the presser foot and the channel opening plow.

As shown in the drawings the machine comprises in general an upper feed roll 10 and a lower feed roll 12 which co-operate to grip the margin or feather of a sole; a plow 14 for preliminarily raising the channel lip; a lip turning wheel 16 for turning the raised lip over toward the face of the sole; a frame or head 18 upon which the above-mentioned parts are mounted; and a horizontal main shaft 20 which is journaled in the head 18 and is connected to drive the feed rolls and the lip turning wheel through driving mechanism carried by the head 18.

The main driving shaft 20 is provided at one end with the usual fast and loose pulleys 22 and 24 and is connected with an inclined shaft 26, which carries the upper feed roll, by means of intermeshing bevel gears 28 and 30 on the shafts 20 and 26, respectively. The

lower feed roll 12 is carried by a shaft 32 which is mounted in parallel relation with the shaft 26 and is driven from the latter by means of a gear 34 secured thereto which 5 meshes with a gear 36 fixed to the shaft 32. A spur gear 38 on the main driving shaft 20 meshes with a gear 40 on a counter shaft 42 journaled in bearings 44 and the counter shaft 42 drives a short horizontal shaft 46 10 through intermeshing bevel gears 48 and 50 on said shafts respectively. The shaft 46 extends at right angles to the counter shaft 42 and the lip turning wheel is carried by a shaft 52 which is parallel to the shaft 46 and 15 is driven from the latter through intermeshing spur gears 54 and 56 on said shafts.

The upper and lower feed rolls 10 and 12 are provided with oppositely beveled faces which are arranged to grip the work and to 20 support it with the portion which is to be operated upon disposed in a substantially horizontal plane. The upper feed roll is adapted to engage the upper side of the feather or marginal portion of the sole which 25 lies beneath the channel lip, while the lower feed roll is arranged to engage the unlipped side of the sole margin directly beneath the portion engaged by the upper roll. The work-engaging faces of both feed rolls are 30 knurled or roughened sufficiently to secure effective feeding engagement with the work without unduly marring the surface thereof.

Inasmuch as the lip turning wheel is arranged to wipe transversely across the lip 35 of the sole, as herein described, it necessarily follows that only a comparatively narrow space will be left between the periphery of the lip turning wheel and the feather or margin of the sole for the operation of feeding means upon the upper side of the feather. In the illustrated machine, however, the inclination of the feed roll shafts is such that by employing feed rolls beveled as herein 40 described the sole margin may be firmly gripped and the sole positively and reliably fed by co-operating feed wheels which may be arranged to engage the sole in the plane of rotation of the lip turning wheel without interfering with the movement of the latter. 45 Further to insure that the upper feed wheel shall engage the sole margin at the base of the lip the upper side of said feed wheel is recessed to receive a portion of the periphery of the lip turning wheel and thus to permit 50 the work-engaging face of the upper feed wheel to be located closer to the axis of the lip turning wheel.

The angle of bevel of the work-engaging faces of the feed rolls is such that said faces 55 preferably are not exactly parallel at their points of engagement with the work but are inclined a few degrees relatively to each other, as shown in a somewhat exaggerated manner in Fig. 6, so that the sole will be more tightly and securely gripped along the inner

than along the outer margin of the feather. This construction causes the sole to be securely held against any tendency of its marginal portion to ride edgewise out from between the feed rolls and therefore insures engagement of the rolls with the sole practically throughout the full width of the rolls at all times. Any tendency of the lower feed roll to throw the sole out, on account of the fact that the greatest diameter of the bevel faces 70 of said roll engages the outer edge of the sole margin, is counteracted by having the upper feed roll oppositely beveled so that the greatest diameter of its work-engaging face engages the inner portion of the feather. By 75 reason of this construction a balanced feed is secured with respect to any tendency of the feed rolls to produce widthwise movement of the feather relatively thereto.

Inasmuch as the feed rolls are maintained 80 in engagement with the full width of the feather throughout the operations upon the shoe, the upper feed roll will be held at all times against the base of the lip and thus it may be relied upon to perform a guiding 85 function taking the place of the usual edge gage so that use of the latter may be dispensed with. The slight difference in inclination of the bevel faces of the feed rolls at their points of engagement with the work 90 further greatly facilitates the turning or swinging of the sole as the more or less sharply curved portions of the sole margin are being operated upon. This is on account 95 of the fact that the sole is capable of pivoting 100 about the region adjacent to the base of the channel lip where the sole margin is gripped more tightly by the feed rolls, whereas the stock adjacent to the outer edge of the feather is capable of moving relatively to the feed 105 rolls without undue frictional rubbing since the feather is more lightly gripped at its outer edge. The angle of bevel of the face of the lower feed roll is such as to insure against liability of the edge of the roll to dig into 110 the face of the sole when the abruptly bent portion at the junction of the shank and forepart is reached. Thus, injury to the stock is prevented and engagement is secured between 115 the sole and the lower feed roll throughout the entire width of the latter during the period of operation in the vicinity of the break between the shank and forepart of the sole, thus preventing the advance of the sole 120 from being retarded at this point.

In order that the work shall be yieldingly gripped between the feed rolls and to enable the rolls to be separated to permit insertion and removal of the work, the lower feed roll shaft 32 is slidably mounted in its bearings in 125 the head 18 and is normally urged upwardly by means of a spring 60 (Fig. 1) secured at its upper end to a portion of the head 18 and at its lower end to the downwardly extending arm of a lever 62 which is maintained in sup- 130

porting engagement with the lower end of the feed roll shaft 32 by the action of the spring 60. The lever 62 is pivoted to the head 18 at 64 and the upper arm of the lever carries an 5 adjustable stop screw 66 arranged to bear against a portion of the head 18 to limit the upward sliding movement of the shaft 32. To prevent contact of the feed rolls with one another when no work is present between 10 them, adjustment of the stop screw 66 may be made for the purpose of varying the limit of approach of the feed rolls. The lower end of the shaft 32 protrudes below its bearing in the head 18 and is encircled by a spring 68 15 which is compressed between the shaft bearing and a collar or washer 70 carried by the shaft. The spring 68 tends to urge the shaft 32 downwardly against the upward pull of the spring 60; but being weaker than the latter 20 spring is effective to separate the feed rolls only when the lever 62 is swung downwardly by means such as a foot treadle, not shown, which may be connected through a treadle rod 72 with the lever 62. On account of the 25 inclination of the lower feed roll shaft 32 the shaft does not slide downwardly within its bearings readily in response to downward pressure vertically directed against the lower feed roll and consequently said feed roll is 30 supported with sufficient rigidity to sustain the work against the action of the lip turning wheel but will yield if unusual resistance is encountered by the wheel as it wipes across the lip of the sole.

35 The lip turning wheel 16 is arranged to rotate in a plane at right angles to the direction of work feed and is designed to turn the lip by a series of yielding blows which are delivered in rapid succession, each blow being followed 40 by a wiping action progressing transversely across the lip from the base to the free edge thereof in a direction at right angles to the length of the lip. To this end, the lip turning wheel is provided with a plurality of beating and wiping rolls 76 which are mounted between the marginal portions of two disks 45 78 and 80 and the rolls are retained in place by means of pins 82 carried by said disks. As shown, the disk 78 is formed with a hub 84 which is fixed on the shaft 52 while the disk 50 80 is provided with a hub 86 which is fixed upon the hub 84 of the other disk. The disks 78 and 80 are held apart by means of a spacing collar 88 which encircles the hub 84. The 55 pins 82 extend from one disk to the other in parallel relation to the shaft 52 and are secured at their ends to the respective disks.

In order that the rolls shall exert a yielding 60 beating and wiping action upon the lip they are axially bored to provide central apertures of greater diameter than the diameter of the pins 82. The rolls are thus loosely mounted 65 upon the pins 82 and as a result when the lip turning wheel is in rotation the rolls 76 will normally be maintained by centrifugal force

at the outermost limits of radial movement determined by the pins 82. The feed rolls 10 and 12 are so located vertically with respect to the lip turning wheel as to position the work with respect to the path of movement 70 of the rolls 76 so that as said rolls successively engage the lip they will yield inwardly toward the axis of the lip turning wheel and will be yieldingly urged outwardly by 75 centrifugal force as they move transversely of the lip, thus insuring yielding wiping engagement of each roll with the lip throughout the full width of the latter. Thus each roll 76 initially engages the lip at the base thereof with a beating action which is immediately followed by a yielding rubbing or wiping action toward the free edge of the lip. As hereinbefore mentioned the angle of inclination of the lower feed roll shaft and the strength of the spring 60 is sufficient to insure 80 that the work will be adequately supported against the downward thrust exerted against the lip by the lip turning wheel.

To insure maximum efficiency in the turning 90 of the lip and to avoid interference with the continuous and uniform feed of the work provision is made, in the illustrated machine, for enabling the lip turning rolls to move endwise in the direction of work feed while they are in wiping engagement with the 95 work. This is accomplished by spacing apart the disks 78 and 80 a distance greater than the width of the rolls 76 and thus providing for a limited amount of axial movement of each roll while it is in engagement with the 100 lip. Normally the rolls are maintained in engagement with the disk 80 which is in advance of the disk 78 in the line of feed, by means of light spring fingers 90 which are formed by making a series of radial cuts or notches in a spring disk 92 which is centrally apertured to encircle the hub 84 of the disk 78 and is conveniently clamped between said disk and the collar 88. The outer ends of the fingers 90 are notched to enable the fingers to straddle the pins 82 so that they will bear against the end faces of the rolls 76. By reason of the above-described construction, as plainly shown in Fig. 4, each roll 76 is free to move axially, or in the direction of 105 work feed, against the force of the light spring fingers 90 while in actual engagement with the work. Inasmuch, therefore, as the lip turning wheel rotates in a plane at right angles to the length of the lip, the above described construction and arrangement of the lip turning rolls enables them to wipe across the lip in a direction at right angles to the length of the lip, notwithstanding the continuous advance of the work. In this way 115 the lip is turned in a most efficient manner in simulation of well-known hand methods of lip turning which have always given most satisfactory results. By enabling the lip turning rolls to move endwise with the work 120 125 130 135

as the latter advances frictional rubbing of the lip lengthwise across the rolls is avoided and there is no resulting objectionable drag imposed upon the work. As each roll leaves 5 the lip the respective spring finger 90 restores the roll to the vertical plane of the other rolls so that it is ready to move axially with the work when it is again brought into engagement therewith.

10 On account of the spaced relation of the disks 78 and 80, which permits the above-described axial movement of the rolls 76 to take place, the rolls 76 are also rendered capable of tilting or angular adjustment upon 15 the pins 82, thus enabling the rolls to tilt as may be required to accommodate themselves to inequalities of the lip. Normally, however, the rolls are maintained in the vertically alined untilted positions shown in Fig. 2 by the action of the spring fingers 90. As 20 shown in Fig. 1, the lip turning wheel, as well as the driving gears 54 and 56 and a portion of the upper feed wheel 10 are enclosed within and protected by a two-part 25 hollow casing 98, the casing being open at its lower portion to permit the lip turning wheel and the upper feed roll to operate on the work.

To enable the lip turning rolls 76 properly to engage the lip to turn it over against 30 the face of the sole the lip is preliminarily raised by the action of the stationary plow 14 which is located just in advance of the lip turning wheel in the line of feed. As shown in Fig. 2, the plow 14 is formed with an upwardly extending shank portion 100 which is received with provision for vertical adjustment within a socket formed upon the exterior of the casing 98.

Figs. 7 and 8 illustrate an alternative form 40 of the invention in which a lip turning wheel of modified construction is employed. As shown in these figures the lip turning wheel, which is indicated at 104, is in the form of a single disk or wheel having its periphery 45 notched to provide a plurality of lip turning teeth or projections 106 each of which is provided with a curved lip-engaging face. Inasmuch as no yielding action is provided for in the construction of the lip turning wheel 50 104 the wheel itself is yieldingly mounted so that it will yield bodily upward as the teeth 106 successively engage the lip and will be yieldingly pressed downward as said teeth wipe across the face of the lip, thereby insuring 55 wiping contact of each tooth throughout the full width of the lip as the tooth moves across the lip. To this end the shaft which carries the lip turning wheel 104 is journaled in a casing member 108 which is pivotally mounted 60 upon the shaft 46 and is acted upon by a spring 110 which tends to swing the casing 108 and consequently the lip turning wheel, downwardly about the axis of the shaft 46 to an extent limited by a stop in the form of 65 a nut 112 threaded upon a bolt 114 which is

pivottally mounted at 116 and extends through the spring 110 and through a lug 118 on the casing member 108, the stop 112 coating with the lug 118 to perform its limiting function. The nut 112 may be turned to adjust the normal vertical relation of the lip turning wheel to the lower feed rolls. As shown in Fig. 8 70 the lip turning wheel 104 is mounted with provision for a limited amount of axial movement upon its supporting shaft against the action of a coiled spring 120 which encircles 75 said shaft. This construction tends to prevent injury to the work such as might occur when operating upon a lip having inequalities therein, the feed wheel yielding in the direction of feed to facilitate passage of the wheel over said portions of the lip. If desired a presser foot, such as that shown at 122 in Fig. 8, may be employed for engaging the 80 lip after it has been acted upon by the lip turning wheel to set the lip in its final position. A presser foot of this character is particularly useful also for the purpose of preventing undue puckering or buckling of the lip at the toe of the sole. 85

It will be seen from the foregoing that reliable work feeding means has been provided which feeds the work positively so as to advance the lip progressively into the field of operations of the lip turning wheel and which 90 performs its feeding function without marring the tread face of the sole or injuring the stock as by undue frictional rubbing contact therewith. The work feeding means has been arranged to permit the sole to be turned 95 readily as the more or less sharply curved portions of its margins are being operated upon; and to operate effectively upon molded soles, such for example as those having so-called cottage-roof shanks, without tending to distort or flatten out the molded contour of the sole, and more especially to avoid breaking down the abrupt bend between the shank and forepart of molded soles of this general type. 100

Having described my invention, what I 110 claim as new and desire to secure by Letters Patent of the United States is:

1. In a machine of the class described, the combination with means for continuously feeding a lipped sole, of means for exerting 115 a wiping action upon the moving lip at right angles to the length of the lip to turn the lip over toward the face of the sole.

2. In a machine of the class described, the combination with means for continuously feeding a lipped sole, of means for preliminarily raising the lip of the sole, and means for engaging the raised lip and wiping across it in a direction relative to the moving lip at right angles to the length of the lip to turn 120 the lip over toward the face of the sole.

3. In a machine of the class described, in combination, a rotary lip turning device for wiping transversely across the lip of a sole, and feed wheels rotatable about parallel axes 125 130

and arranged to engage opposite sides of the sole margin in the plane of rotation of the lip turning device to advance the lip progressively therewith.

5. 4. In a machine of the class described, feed rolls rotatable about parallel axes and arranged to support and feed a sole by engagement with opposite sides of the feather, and a lip turning wheel rotatable in a plane transverse to the direction of feed and arranged to engage the lip in the common axial plane of the feed rolls and at a point immediately adjacent to the bite of said rolls.

5. In a machine of the class described, the combination with a rotary lip turning tool, of feed rolls having their axes substantially parallel to each other and at right angles to the axis of said tool and their peripheries shaped to engage opposite sides of a lipped sole and to support the portion of the sole engaged thereby in a plane oblique to the axes of the feed rolls.

6. In a machine of the class described, in combination, means for raising the lip of a lipped sole, and a plurality of independently yieldable beater members movable in succession across the raised lip in a direction substantially perpendicular to the edge of the lip to turn the lip over against the face of the sole.

7. In a machine of the class described, in combination, means for raising the lip of a lipped sole, and means movable through a closed path in a plane substantially perpendicular to the plane of the sole for delivering a succession of hammer-like blows to the raised lip and subsequently wiping yieldingly across the lip to turn the lip over against the face of the sole.

40. 8. In a machine of the class described, a rotary device, and a plurality of lip-engaging members mounted thereon for independent yielding movement in a direction longitudinal to the axis of rotation of said device, whereupon the rotation of said device will cause said members to move across the lip of a sole fed longitudinally through the machine, and each member will yield longitudinally to accommodate the travel of the lip.

50. 9. In a machine of the class described, in combination, means for supporting and feeding a sole, a rotating wheel, and a lip turning member carried by said wheel and movable relatively thereto upon rotation of the wheel yieldingly across the lip to turn the lip.

10. In a machine of the class described, in combination, means for feeding a lipped sole, a rotary device rotating in a plane at right angles to the length of the lip, and means on said device for yieldingly engaging the lip to turn it over against the face of the sole.

11. In a machine of the class described, in combination, means for supporting and feeding a lipped sole, and a wheel having members mounted thereon, said members being

capable of yielding inwardly during rotation of the wheel and arranged to traverse the path of the lip to turn the lip.

12. In a machine of the class described, in combination, means for feeding a lipped sole, a device rotating in a plane at right angles to the length of the lip, and lip engaging members carried by said device with provision for movement in the direction of feed of the sole.

13. In a machine of the class described, in combination, means for feeding a lipped sole, a wheel carrying a work engaging member movable with the work and relatively to said wheel during its period of engagement with the work, and means for returning said member to its normal position relatively to the wheel during its period of disengagement from the work.

14. In a machine of the class described, in combination, means for raising the lip of a sole being fed through the machine, and a wheel revolving in a plane at right angles to the path of the lip and carrying peripheral members constructed and arranged yieldingly to engage the raised lip to turn it beyond its raised position.

15. In a machine of the class described, in combination, means for raising the lip of a sole being fed through the machine, a wheel revolving in a plane at right angles to the path of the lip, and a plurality of members mounted in the peripheral portion of the wheel for rotary movements relatively to the wheel for engaging the raised lip to turn the lip over against the face of the sole.

16. In a machine of the class described, in combination, means for raising the lip of a sole being fed through the machine, a wheel revolving in a plane at right angles to the path of the lip, and a plurality of rolls loosely mounted in the peripheral portion of the wheel with their axes substantially parallel to the axis of the wheel for yielding engagement with the raised lip to turn it beyond its raised position, said rolls being mounted for limited axial movement in the wheel.

17. In a machine of the class described, a lip turning wheel comprising in combination, a shaft, a pair of disks affixed in spaced relation upon the shaft, a plurality of lip-engaging rolls mounted for limited radial and axial movement between the peripheries of said disks, and spring means for normally holding said rolls in engagement with one of said disks.

18. In a machine of the class described, in combination, means for feeding a lipped sole through the machine, a rotating wheel, and a lip turning member carried thereby and adapted, upon rotation of the wheel, to be moved transversely across the lip to turn the lip, said member upon engagement with the lip being movable inwardly from an outward position in which it is normally main-

tained by centrifugal force during rotation of the wheel.

19. In a machine of the class described, in combination, a rotating wheel, a plurality of beater members spaced about the periphery of the wheel and capable of being normally held in an outward position by centrifugal force during rotation of the wheel, and means for feeding a lipped sole across the path of said beater members in a direction to enable the latter to turn the lip.

20. A lip turning machine having, in combination, a rotary supporting wheel and a lip engaging member mounted thereon adjacent to the periphery of said supporting wheel for radial and axial movement relatively thereto.

21. In a lip turning machine, the combination with a rotary supporting wheel, of a lip engaging member loosely mounted thereon adjacent to the periphery of the wheel for rotation with the wheel and for bodily movement in a direction parallel to the axis of the wheel.

22. In a machine of the class described, in combination, a lip turning member mounted for movement in the direction of the path of the lip of a sole being fed through the machine, and transversely across said path, and in a direction substantially perpendicular to the plane of the sole.

23. In a machine of the class described, in combination, a lip turning member mounted for yielding movement across the path of the lip of a sole being fed through the machine, said member being movable also in the direction of feed in unison with the sole during its period of engagement with the lip.

24. In a machine of the class described, in combination, a lip turning member mounted upon the peripheral portion of a supporting wheel for movement with the supporting wheel across the lip of a sole being fed through the machine and also for movement independently of the supporting wheel in the direction of feed of the sole, and means for moving said member opposite to the direction of feed while it is disengaged from the lip of the sole.

25. In a machine of the class described, in combination, a rotating wheel, a beater member carried by said wheel and adapted to be moved upon rotation of the wheel transversely across the lip of a sole being fed through the machine to turn the lip, said member being capable of being displaced relatively to the wheel from its normal plane of rotation by the movement of the sole, and yielding means for returning said member to said plane upon being disengaged from the sole.

26. In a machine of the class described, in combination, a member engageable with the lip of a sole fed through the machine and movable both in unison with the lip throughout its period of engagement therewith and relatively to the lip to turn the lip without op-

posing the feed of the sole, and means for moving said member relatively to the lip.

27. In a machine of the class described, in combination, means for feeding a lipped sole to advance the lip progressively in a lengthwise direction through the machine, and means traversing the path of the lip to turn the lip, said means being movable also in unison with the lip during its period of engagement therewith.

28. In a machine of the class described, in combination, means for feeding a lipped sole to advance the lip progressively in a lengthwise direction, and means traversing the path of the lip to turn the lip, said means being capable of independent bodily movement in the direction of feed of the sole.

29. In a machine of the class described, in combination, means for feeding a lipped sole to advance the lip in a lengthwise direction, a lip turning member movable in unison with the lip as the sole is fed, and means for moving said member across the path of the lip to turn the lip while said member is moving with the lip.

30. In a machine of the class described, in combination, means for feeding a lipped sole to advance the lip in a lengthwise direction, a lip turning member adapted to be moved by engagement with the lip in the direction of feed of the sole, and means for moving said member across the path of the lip to turn the lip while said member is moving in the direction of feed.

31. In a machine of the class described, in combination, means for feeding a lipped sole to advance the lip in a lengthwise direction, and a lip turning member movable across the lip substantially at right angles to the length of the lip to turn the lip and also lengthwise of the lip to avoid interfering with the feed of the sole.

32. In a machine of the class described, in combination, means for raising the lip of a sole being fed through the machine, and means traversing the path of the raised lip to turn the lip beyond its raised position, said means being movable also in the direction of feed of the sole.

33. In a machine of the class described, in combination, means for raising the lip of a sole being fed through the machine, and means traversing the path of the raised lip to turn the lip beyond its raised position, said means being movable also in the direction of feed of the sole and also in a direction substantially perpendicular to the plane of the sole.

34. In a machine of the class described, in combination, means for raising the lip of a lipped sole, and means movable in a plane substantially perpendicular to the plane of the sole for delivering a succession of yielding, wiping blows to the raised lip to turn the lip over against the face of the sole.

35. In a machine of the class described, a rotary device, means for supporting a lipped sole and feeding its margin progressively past said device, and a plurality of wiper members carried by said device for delivering a succession of wiping blows to the raised lip in a direction transversely across the lip, said members being movable with the work in the direction of feed during their periods of wiping contact with the lip.

36. In a machine of the class described, in combination, a rotary lip turning device arranged with its axis extending in the general direction of the work feed, and co-operating feed rolls for advancing a sole past said device in position to be operated upon thereby, said rolls being arranged with their axes parallel to each other and one of said rolls being shaped to engage the sole at the base of the lip and in the plane of rotation of the lip turning device.

37. In a machine of the class described, a lip turning wheel, a feed roll arranged with its axis at an angle to the axis of said wheel, the periphery of the roll being transversely inclined with respect to its axis, and a second feed roll having its periphery transversely inclined with respect to its axis for engaging

the opposite side of the sole margin and co-operating with the first feed roll to feed the sole past the lip turning wheel.

38. In a machine of the class described, in combination, a rotary lip turning device, two parallel shafts, co-operating feed rolls one on each of said shafts, said rolls having peripheral faces transversely disposed at such angles to their respective axes that they will co-operate to grip the work more tightly along the inner than along the outer portions of the margin of the work.

39. In a machine of the class described, the combination with means for continuously feeding a lipped sole, of a lip turning member movable across the lip and constructed and arranged to move also with the lip while in contact with the lip.

40. In a machine of the class described, the combination with means for continuously feeding a lipped sole, of a lip turning member movable across the lip and constructed and arranged to partake of the feeding movement of the lip while in contact with the lip.

In testimony whereof I have signed my name to this specification.

FREDERIC E. BERTRAND.
